END CAP FOR GOLF CLUB GRIPS

Harold G. Barrett, Wilmette, Ill.

Application March 4, 1931. Serial No. 519,943

4 Claims. (Cl. 273—80)

This invention relates to end caps for golf club grips and the like.

The salient objects are to securely fasten the ends of grips for golf clubs and the like; to protect the ends of such grips to prevent damage thereto and the resulting fraying and the like thereof; to expedite installation and removal of the grips; and to provide a novel cap of pleasing appearance and economical manufacture.

Other objects will appear hereinafter.

In the selected embodiment of my invention illustrated in the accompanying drawing

Fig. 1 is an elevational view of a golf club grip having my novel cap associated therewith;

Fig. 2 is a vertical sectional view showing the grip as arranged prior to the installation of my cap;

Fig. 3 is a similar sectional view showing my cap installed;

Fig. 4 is a transverse sectional view of my cap and a plug used therewith, these parts being shown separated;

Fig. 5 is a top plan view of the cap; and

Figs. 6 and 7 are views of modified forms of construction.

Golf clubs are customarily carried in bags having an open upper end through which the head ends of the clubs are extended whereby the grip or handle ends thereof rest on the bottom of the bag. These grips usually comprise a strap of leather or the like wound about the handle portion of the club and when the ends of these grips are rested on the bottom of the bag the marginal section of the grip is often damaged. Moreover, this marginal section is sometimes struck against objects in the handling of the club and it is not uncommon to find this section of the grip damaged even before the club has been used. The strap providing the grip is spirally wound about the handle portion of the club with the adjacent edges in abutment to thereby provide a smooth uninterrupted surface. The upper end of the strap is usually secured by a tack or other securing means extended into the handle which means is then covered by winding a layer of the strap thereover. This creates a bulge in the grip which is undesirable in that it is uncomfortable and may blister the hands of the user. Further, such securing means is susceptible to unloosening. The foregoing disadvantages and others of a kindred nature are overcome by the novel device constituting my invention which is particularly, though not necessarily, adapted for use with so-called bell-top grips of annular or polygonal cross section. These bell top grips are of a somewhat frusto-conical configuration with the greatest diameter or flared end thereof disposed at the outer end of the shaft of the club. In the

depicted embodiment of the invention this configuration is provided on the body member of the grip in the nature of an end plug 6 which is inserted into the hollow metal shaft 7 of the club. However, when the invention is used with a wooden shafted club this configuration will be provided on the upper end of such a shaft. The plug 6 and the adjacent portion of the shaft 7 provide the handle of the club on which the usual cushion 8 is arranged. The grip or grip covering includes a leather strap 9 or the like spirally wound about the handle with the upper marginal section 10 thereof extending beyond the end of the plug 6. On the end of the plug, centrally thereof, is a boss 11 of a height slightly greater than the thickness of the strap. My novel cap is preferably made from sheet material. If desired it may be made of metal or a material like, or substantially like, pyroxylin. If made of metal it will be suitably finished as by polishing or plating and when made of pyroxylin or like material it may be made in one or more colors or in any other manner to increase aesthetic appearance thereof. The peripheral configuration of the cap will be similar to the cross section of the handle. The cap may be formed by pressing it into the desired shape and the medial portion thereof is depressed to provide a flat bottomed depending boss 12 having a countersunk opening 13 there-in, the formation of this boss defining a recess 14 opening into the top of the cap designated by 15. At the periphery of the cap is a depending flange 16, the free edge of which is chamfered as indicated at 17, the edge 17 being below the plane of the bottom of the boss 12. Between the flange 16 and the boss 12 a recess or groove 18 is defined. After the strap 9 is arranged on the handle, the marginal section 10 is folded onto the end of the plug 6 toward the boss 11. The cap 15 is then rested on the end of the plug with the chamfered edge 17 embracing the fold in the strap whereby the marginal section 10 will be extended into the groove 18. A screw 19, or other similar fastening means, is then passed through the opening 13 and secured in the end of the plug 6. By tightening this screw the marginal section 10 is securely clamped between the cap 15 and the end of the plug 6 and displacement thereof is thus prevented. The outer face of the flange 16 will be aligned with the outer face of the strap 9 and therefore a smooth end will be formed on the handle, this being aided by the cooperation of the fold in the marginal section 10 with the chamfered edge 17. The end of the strap or grip covering will be covered by the cap and thus fraying and other damage thereto will be prevented. It has been stated that the cap is arranged to be of a pleasing appearance and this

is enhanced by inserting a plug 20 into the recess 14. This plug 20 may be made of a pyroxylin material or the like and may be of a blending or contrasting color relative to the cap 15. The plug not only enhances the appearance but also serves to cover the head of the screw 19 and, moreover, by properly shaping the outer face thereof to conform to the surface of the cap, a smooth surface will be provided on said cap. The plug will be tightly pressed into the recess 14 to prevent displacement and, if desired, a suitable adhesive may be used to further insure against displacement. For example, if the plug be of a pyroxylin material, a small amount of acetone will be introduced into the recess which, by its chemical action on such material, will secure the plug in the recess.

From the foregoing description it is manifest that I have provided a cap for golf club grips and the like which will securely fasten the ends of such grips. Further, the cap will provide a smooth end for the grip and will effectively prevent damage to such end. Moreover, the cap is of pleasing appearance and will greatly enhance the aesthetic appearance of not only the grip but of the club as a whole. Since both the cap and the plug therefor may be made from sheet material, economical manufacture is attained.

30 In Fig. 6 a modified form of construction is shown and herein the cap 15' includes a medial depending boss 12', the flat bottom of which depends below the chamfered edge 17' and is extended into a recess 21 in the end of the plug 6. 35 A screw 19' is extended through the countersunk opening 13' to retain the cap 15' in position. The disposition of the plug in the recess provides a lateral reenforcement for the cap and insures against displacement thereof. A cap 20' 40 is employed to fill the recess 14' and to conceal the head of the screw 19'.

In Fig. 7 a further modification is shown and herein the cap 15'' includes a medial depending boss 12'' having a flat bottom with an enlarged opening 13'' therein. A plug 20'' is passed through this opening and into an enlarged opening 21' in the end of plug 6, acetone or the like being used to secure this plug in the recess. Here, again, lateral or transverse displacement is prevented.

50 While I have illustrated and described a selected embodiment of my invention it is to be understood that this is capable of variation and modification and I therefore do not wish to be limited to the precise details set forth but desire to avail myself of such changes and alterations as fall within the purview of the following claims.

I claim:

60 1. The combination with a golf club grip including a body member and a grip providing portion having the free marginal part thereof folded onto the end of the body member, of an end cap for said grip mounted wholly on the end 65 of said grip and having the outer peripheral edge thereof aligned with the periphery of said grip, said cap having the inner surface thereof adjacent the inner marginal edge thereof spaced from the end of said body member to receive the 70 free marginal edge of the part of the grip providing portion folded onto the end of said body member and having said inner marginal edge engaged with the fold in said grip providing portion at the end of said body member to thereby

clamp said grip providing portion between said marginal edge and the end of said body member, and means for securing said cap to said body member.

2. The combination with a golf club grip including a body member and a grip providing portion having the free marginal part thereof folded onto the end of the body member, of an end cap for said grip mounted wholly on the end of said grip and having the outer peripheral edge thereof aligned with the periphery of said grip, said cap having a medially located depressed part on the inner surface thereof and having the inner marginal edge thereof spaced from said depressed part to provide a pocket in the inner surface of said cap adapted to receive the free marginal edge of the part of the grip providing portion folded onto the end of said body member, said inner marginal edge being engaged with the fold in said grip providing portion at the end of said body member to thereby clamp said grip providing portion between said marginal edge and the end of said body member, and means for securing said cap to said body member.

3. The combination with a golf club grip including a body member and a grip providing portion having the free marginal part thereof folded onto the end of the body member, of an end cap for said grip mounted wholly on the end of said grip and having the outer peripheral edge thereof aligned with the periphery of said grip, said cap having a medially located depressed part on the inner surface thereof and having the inner marginal edge thereof spaced from said depressed part to provide a pocket in the inner surface of said cap adapted to receive the free marginal edge of the part of the grip providing portion folded onto the end of said body member, said inner marginal edge being engaged with the fold in said grip providing portion at the end of said body member to thereby clamp said grip providing portion between said marginal edge and the end of said body member, and means for securing said cap to said body member.

4. The combination with a golf club grip including a body member having a boss on the end thereof and a grip providing portion having the free marginal part thereof folded onto the end of the body member about said boss, of an end cap for said grip mounted wholly on the end of said grip and having the outer peripheral edge thereof aligned with the periphery of said grip, said cap having that part of the inner surface thereof adjacent the inner marginal edge thereof and aligned with the end of said body member and aligned with the portion of said body member about said boss spaced from said portion of said body member to receive the free marginal edge of the part of the grip providing portion folded onto the end of said body member and having said inner marginal edge engaged with the fold in said grip providing portion at the end of said body member to thereby clamp said grip providing portion between said marginal edge and the end of said body member, and means for securing said cap to said body member.

HAROLD G. BARRETT.
